PISTON AND PACKING

Albert B. Root, Jr., Newton, Mass., assignor
to Hunt-Spiller Manufacturing Corporation,
Boston, Mass., a corporation of Massachusetts

Application June 7, 1941, Serial No. 397,057

3 Claims. (Cl. 309—29)

This invention relates to pistons having segmental metallic packing rings spring-pressed into contact with the cylinder wall, and the object is to provide a construction wherein the full effect of the spring on the several segments of the packing is at all times availed of in use.

My invention will be well understood by reference to the following description taken in connection with the accompanying drawings, wherein by way of example I have shown a piston and packing as used in the horizontal cylinder of a steam locomotive and wherein:

Fig. 1 is an edge view of a locomotive piston and its packing rings;

Fig. 2 is a diametrical section on the line 2—2 of Fig. 3, the central portion of the piston being broken away; and

Fig. 3 is a transverse section through the piston at the location of one of the ring grooves, the ring being omitted.

In many applications of pistons they normally take up a position eccentric to the cylinder in which they work and the packing rings therefore project further on one side than on another. A notable example is in the case of a horizontal cylinder as in the case of a steam locomotive wherein the center line of the piston is displaced under gravity downwardly relative to the center line of the cylinder. Herein for convenience and clearness I will refer to such a horizontal piston as representative of the class first referred to and use the words "upper," "lower" and the like, "lower," for example, referring to the side of the cylinder toward which the piston is normally displaced.

Referring now to the drawings, I there show a piston 4 having a pair of ring-receiving grooves 6 receiving piston rings 8, these rings each comprising two series of segments laterally adjacent, the segments in the respective series being staggered. The construction may be generally similar to that disclosed in the patent to Platt, 1,643,628. In the drawings, however, I have illustrated these rings as being of the type commonly referred to as lip rings, the outer portions of the segments having laterally extending flanges or lips 10 which overlie the outer face of the piston adjacent the grooves. The presence or absence of these lips, however, is not of controlling importance in connection with the present invention. They are an example of a construction wherein the lower segment of the ring may support the weight of the piston. Another example would be one wherein the radial depth of the ring, or the combined depth of the

ring and an underlying spring, exceeded the depth of the groove.

Each ring 8 is supported by a spring 12 in the form of a divided or split ring (see Fig. 3) which underlies the segments and normally presses them radially outwardly. Herein the ring 12 is shown as received in its entirety beneath the segments and being of substantially the same width. The groove 6, therefore, in the example shown is of generally rectangular cross section and of sufficient depth to accommodate the spring and the bodies of the segments.

It is desirable that in use the segments of the packing ring be free to rotate relative to the piston to distribute the wear. In certain types of segmental packing rings provision has been heretofore made to lock the supporting spring to the ring segment in such a manner that no relative circumferential movement as between the ring and the springs has been possible. In other constructions wherein such interlock between the spring and the ring is not provided for, the spring and ring probably have relative movement circumferentially with respect to each other and the spring, of course, can move relatively to the piston either with the ring segments or differentially thereto.

Referring now to Fig. 2, the piston and its packing are there shown in the position taken in use when the packing is restrained by the cylinder wall. The piston body settles under gravity until it is supported at its lowermost point by the packing. In the example illustrated the lips 10 seat on the piston face and the bottom of the segments seat on the spring 12 which in turn rests on the bottom of the groove 6. At the upper portion of the cylinder the piston face is correspondingly retracted from the cylinder wall and the segments 8 must therefore be pressed out by the spring 12 to engage the wall in the manner indicated in the drawings. A similar condition in varying degree is found at other portions of the circumference.

Let us suppose now the split of the spring 12 to be at the bottom of the cylinder, that is, in such a position as would be indicated by turning Fig. 3 upside down. The ends of the spring 12 are then subject to being clamped by the overlying segment of the packing and in that case the spring would become essentially an unbroken circle and the resultant supporting effect, notably at the upper side of the piston, be severely limited. In an intermediate case corresponding, for instance, to a rotation of Fig. 3 clockwise through an angle of 90° with the break between the ends

of the spring displaced to three o'clock position, the portion of the spring then at the bottom of the cylinder may be similarly clamped, leaving at the right a short, relatively inflexible arm, while the effective supporting action of the spring at the top of the cylinder would be restricted to one arm thereof.

In accordance with my invention I therefore provide means for locking the spring 12 in the groove 6 with the break between the ends of the former permanently positioned at the upper portion of the piston while preserving the freedom of movement of the segments in the groove. Herein I have shown this as effected by providing at the central portion of the spring 12 opposite the split an inwardly projecting pin or stud 14 adapted to enter a hole drilled to receive the same in the bottom of the piston ring groove at such a point that when the piston is applied to the cylinder the hole shall be at the bottom of the cylinder. Other means for preventing circular rotation of the ring within the piston ring grooves obviously may be provided.

With this construction, as is seen by reference to Figs. 2 and 3, those segments of the packing ring at the top of the cylinder which have the greatest range of movement and require the most efficient support receive it from the two ends of the spring and its resilient reaction is proportioned to the demands thereon at other parts of the circumference.

It may be noted that in Fig. 3 I have not attempted to show the spring 12 expanded but rather in the position in which it would be held by the packing ring when the piston is in the cylinder, although the ring itself is not shown in the figure.

I am aware that the invention may be embodied in other specific forms without departing from the spirit or essential attributes thereof,

and I therefore desire the present embodiment to be considered in all respects as illustrative and not restrictive; reference being had to the appended claims rather than to the foregoing description to indicate the scope of the invention.

I claim:

1. A piston for horizontal operation having a ring-receiving groove, a packing ring therein formed of a number of segments, a spring in the form of a divided ring beneath the segments, the spring and ring as an assembly having a radial depth greater than the depth of the groove whereby the ring may support the weight of the piston, and means independent of the segments 10 for positioning the spring with the division point thereof at the upper portion of the piston.

2. A piston for horizontal operation having a ring-receiving groove, a packing ring therein formed of a number of segments and being free for circumferential movement in the groove, a divided spring ring supporting the segment, the spring ring and packing ring as an assembly having a radial depth greater than the depth of the groove whereby the ring may support the weight of the piston, the spring ring having its central portion secured against circumferential movement to the piston body adjacent the lowermost portion thereof.

3. A piston for horizontal operation having a ring-receiving groove, an incompletely annular spring in the groove, means for positioning the same to locate its ends at the top of the piston and circumferentially movable packing ring segments in the groove and overlying the spring, the spring and ring as an assembly having a radial depth greater than the depth of the groove, whereby the ring may support the weight of the piston.

ALBERT B. ROOT, JR.
